UNITED STATES PATENT OFFICE.

JAMES WILL TRACY, OF SMITHLAND, KENTUCKY.

DESIGN FOR A CANE OR SIMILAR ARTICLE.

Application filed December 2, 1922. Serial No. 4,468. Term of patent 14 years.

To all whom it may concern:

Be it known that I, JAMES WILL TRACY, a citizen of the United States, residing at Smithland, in the county of Livingston and State of Kentucky, have invented a new, original, and ornamental Design for a Cane or Similar Article, of which the following is a specification, reference being had to the accompanying drawing, forming part thereof.

The figure is a perspective view of a cane, showing my new design.

I claim:

The ornamental design for a cane, or similar article, as shown.

JAMES WILL TRACY.
